UNITED STATES PATENT OFFICE.

ALBERT P. BALL, OF ROYAL OAK, MICHIGAN, ASSIGNOR TO SQUARE D COMPANY, OF DETROIT, MICHIGAN, A CORPORATION OF MICHIGAN.

QUICK-BREAK DOUBLE-THROW SWITCH.

1,400,343.

Specification of Letters Patent.

Patented Dec. 13, 1921.

Application filed June 17, 1918. Serial No. 240,376.

To all whom it may concern:

Be it known that I, ALBERT P. BALL, a citizen of the United States, residing at Royal Oak, in the county of Oakland and State of Michigan, have invented certain new and useful Improvements in Quick-Break Double-Throw Switches, of which the following is a full, clear, and concise description thereof.

10 My invention relates to quick break double throw switches, which may be of the armor clad or inclosed type.

An object of this invention is to provide a quick break at each throw of a double 15 throw switch.

A further object of this invention is to simplify the construction of quick break double throw switches, whereby the desired objects are secured with a minimum number 20 of parts.

A further object of this invention is to so design the parts of this switch mechanism that a very rugged and practically fool proof structure results.

25 A further object of this invention is to provide a center stop to catch and retain the quick break switch in neutral position.

A further object of this invention is to provide an outside lock off for this double 30 throw switch.

A further object of this invention is to so design the switch that it is normally possible to secure only a very rapid continuous motion from one extreme position to the other 35 extreme position.

One of the many possible forms that this invention may take is shown in the accompanying drawings, in which—

40 Figure 1 is a perspective view of the double throw switch with an inclosed casing shown in dotted lines.

Fig. 2 is a detailed sectional fragmentary view of the switch mechanism.

Referring to the drawings, it will be seen 45 that the switch is inclosed in a casing 1 which may be of metal or other suitable material. The switch mechanism comprises stationary contacts 2 arranged in two places or pairs, as may be seen from Fig. 1.

50 The movable contacts are of the pivoted type and are pivoted at their central portion to a member 3. These movable contacts each comprise two integral arms 4 at an angle to each other substantially in the shape of a 55 V, as is clearly shown in Fig. 2. These mov-

able contact members are joined by means of cross heads 5, which may be formed from a metal bar provided with insulating sleeves 6. These sleeves are fastened to the bar and to said movable contacts by means of clips 7, or clamping members. Rigidly mounted upon the cross heads 5 is a yoke member 8. This yoke comprises two spaced plates 9, which are held in their spaced relation by means of bolts and spacing elements thereon, indicated by the reference character 10. This yoke member is provided at each end with lugs 11, the purpose of which will appear later.

The construction above described is strong 70 and substantial and not so likely to get out of alignment or to be bent out of shape when roughly used as one in which the tips of the V-shaped blades are free. This follows from spacing of the cross-heads 5 and from inter- 75 connecting the yoke member 8 to the cross-heads. The blades have no projecting parts and can readily be cut from stock sheet material without waste.

The switch mechanism is controlled and 80 operated by a suitable operating member, such as shown at 12, which comprises a horizontal portion, which constitutes together with upright portions and pivoted parts, a large crank carried inside of the casing. A 85 portion of this operating member extends to the outside and comprises an upright member 13 and an operating crank 14. This operating member 12 is connected to the yoke solely by means of a resilient member or 90 spring 15, which is fastened at one end to said operating member and at the other fastened by means of suitable bolt, rivet or other device 16 to the yoke. Upon movement of this operating member to thereby move the 95 internal or switch mechanism, the operating member contacts with the lugs 11 and thereby moves said yoke, cross heads and movable contacts over in the direction in which said operating member is moving. This is continued until the switch is positively closed. When it is desired to open the switch, the operating member is moved toward neutral or upright position, and in so doing engages the other lugs 11 from those formerly engaged, and serves to positively initiate the opening of the switch. When the frictional engagement of the movable and stationary contacts reaches a fairly low value, the spring 15, which has previously been ten- 110

sioned by the motion of the operating member serves to suddenly withdraw the movable contacts from engagement with the stationary contacts and thereby produce a quick
5 break.

Inasmuch as there is a tendency in quick break double throw switches for the switch mechanism to move over to an extreme limit of its stroke, it is found advisable to provide some type of center stop for these double throw quick break switches. Said center stop as shown in Fig. 1 comprises a fixed flanged plate 16 having pivoted thereon an outwardly sprung pressed plate 17 provided
10 with a notch 18, adapted to receive the upright portion 13 of the operating member and temporarily retain the same in upright or neutral position. This movable plate 17 has inclined faces or edges 19 on either side
15 of notch 18, which are adapted to be engaged by the vertical member 13 and serve to depress the movable plate 17 until the operating member 13 arrives at the central position, at which time the movable plate 17
20 snaps outwardly and the notch 18 engages the upright portion 13 and retains the same in neutral position. This is of special importance when the switches are so mounted that gravity will urge the blades toward one
25 set of fixed contacts.

However, in certain types of electrical work or installations, it is desirable to have a double throw switch adapted to be thrown rapidly from one extreme position to the other extreme position, as in motor starting, for example. Such a rapid motion of this double throw switch is permitted by the center stop illustrated. When the switch mechanism is moved through the medium of the operating member rapidly, from one extreme position to the other extreme position, the part 13 of the operating member rides along one of the inclined faces 19 and due to this rapid motion depresses this movable plate 17
35 with considerable speed and the momentum thereby acquired serves to withdraw the notch 18 from the path of motion of member 13 and allows its free passage from one extreme position to the other extreme position.
40 45 50 55 60

It will be further noted upon reference to this center stop that the movable plate 17 and the stationary plate 16 are provided with alining openings 20, which are adapted to receive the bail or hook shaped portion
65 of a padlock or similar locking means.

Large holes are provided in the stationary plate 16 as indicated at 21, which are very much larger than the openings 20 and are adapted to accommodate the bail portion of a large padlock or other means. It will be
70 seen that applicant has further provided an outside lock off by means of which it is possible to lock the switch in neutral position against subsequent operation.

It will be seen from the above detailed description and drawings that applicant has provided a very simple device, which is capable of a great many uses and has a great number of functions. For example, he has provided a double throw quick break switch
75 equipped with means whereby it may be operated as a double throw switch in the usual manner and stopped or temporarily retained in neutral position, and has further provided means which insures a quick motion from
80 one extreme limit to the other extreme limit, and has further provided means whereby the switch may be locked in off position.

It is intended that all matters shown and described in this detailed description and drawings shall be interpreted as illustrative and not in a limited sense, as it is intended that the invention herein disclosed shall be limited only as defined by the claims.

Having thus described my invention, what I claim is:

1. A quick break double throw switch comprising a plurality of stationary and movable contacts, said movable contacts having a plurality of integral arms, a yoke 100 rigidly connected to said movable contacts, an operating member, and resilient means connecting the operating member to a point on said yoke intermediate the ends thereof.

2. A quick break double throw switch 105 comprising a plurality of stationary and movable contacts, said movable contacts having a plurality of integral arms, a yoke rigidly connected to said movable contacts, an operating member, and resilient means 110 interposed between said yoke and operating member, and connecting the operating member to substantially the mid-point of said yoke, said operating member extending transversely of, and adapted to contact 115 with, said yoke.

3. A quick break double throw switch comprising stationary and movable contacts, said movable contacts having connecting cross heads, a yoke rigidly fastened to said connecting cross heads and having engageable portions, an operating member positioned outside the yoke but adapted to contact with the engageable portions of said yoke, and resilient means interposed between said operating member and an intermediate point on said yoke.

4. A quick break double throw switch comprising stationary and movable contacts, said movable contacts comprising a plu- 130

rality of integral arms extending at an angle to each other and having connecting cross heads, a yoke rigidly fastened to said connecting cross heads, an operating member adapted to contact with said yoke, said member extending transversely of said yoke and within the angle formed by said blades, and resilient means connected to said operating member and said yoke.

10 5. A quick break double throw switch comprising stationary and movable contacts, a yoke rigidly fastened to said movable contacts and provided with lugs, an operating member adapted to contact with said lugs and resilient means connecting said operating member to an intermediate point on said yoke.

20 6. A quick break double throw switch comprising stationary and movable contacts, a yoke rigidly fastened to said movable contacts and provided with lugs, an operating member positioned between said lugs and adapted to contact with said lugs and resilient means connecting said operating member and yoke.

25 7. In a double throw switch, a plurality of centrally pivoted V-type blades, means rigidly and insulatively interconnecting the corresponding ends of the blades, comprising independent cross-heads, and a yoke extending from one cross-head to the other, said yoke being fixed to the cross-heads and comprising a plate having upstanding lugs near its ends.

30 8. In a quick break switch, a plurality of centrally pivoted V-type blades, means rigidly and insulatively interconnecting the ends of the blades, comprising independent cross-heads, a yoke comprising a plate fixed relative to the cross-heads and interconnecting them and provided with upstanding lugs near its ends, an operating member adapted to engage either of the lugs, and a spring between the intermediate portion

40 45 of the yoke and the operating member.

9. In a quick break switch, a plurality of centrally pivoted V-type blades, means rigidly and insulatively interconnecting the ends of the blades, comprising independent cross-heads, a yoke comprising a plate fixed relative to the cross-heads and interconnecting them and provided with upstanding lugs near its ends, an operating member

adapted to engage either of the lugs, and a spring between the intermediate portion 55 of the lug and the operating member, said operating member being a U-shaped crank pivoted substantially in alinement with the blades.

10 10. A quick break double throw switch, 60 comprising a plurality of centrally pivoted V-type blades, sets of fixed contacts co-operable with the ends of the blades, and means for operating the blades, comprising an inverted bail-shaped operating crank pivoted approximately in alinement with the blades, said crank spanning the blades, and intermediate resilient connections between the crank and blades, said means being 65 confined within the dihedral angle determined by the blades.

11. In a quick break switch, a plurality of centrally pivoted V-shaped blades, means rigidly and insulatively connecting the ends of said blades comprising independent cross-heads, a yoke embodying parallel positioned plates fixed relatively to the cross-heads and interconnecting them, said plates having upstanding lugs near their ends, an operating member adapted to engage either 75 of the lugs, and a spring connecting said operating member and a point intermediate the ends of said plates and between said plates.

12. A quick break double throw switch 80 comprising a plurality of stationary and movable contacts, said movable contacts comprising integrally formed V-shaped arms, a yoke member extending between the arms and provided with engageable portions, an operating member adapted to engage said portions, and a spring connecting said member to the yoke intermediate 85 said engageable portions.

13. A quick break double throw switch 90 comprising a plurality of stationary and movable contacts, said movable contacts comprising integrally formed V-shaped blades, a yoke member extending between the blades and provided with engageable portions, an operating member positioned without and above the yoke and adapted 100 to engage said portions, and a spring connecting said operating member to the yoke intermediate said engageable portions.

ALBERT P. BALL.
